United States Patent Office

Des. 179,162

Patented Nov. 6, 1956

179,162

AUTOMOBILE LAMP OR SIMILAR ARTICLE

John Sinko, Oak Park, Ill., assignor to Sinko Mfg. & Tool
Co., a corporation of Illinois

Application March 30, 1956, Serial No. 40,856

Term of patent 14 years

(Cl. D48—32)

Figure 1 is a side elevational view of an automobile lamp or similar article embodying my new design;

Fig. 2, a rear elevational view;

Fig. 3, a front elevational view; and

Fig. 4, a top plan view.

I claim:

The ornamental design for an automobile lamp or similar article, as shown.
